ARTICULATED CAR

John Christiansen, Berwick, Pa., assignor to
American Car and Foundry Company, New
York, N. Y., a corporation of New Jersey

Application May 9, 1934, Serial No. 724,650

8 Claims. (Cl. 105—4)

This invention relates to articulated cars; namely, that type in which the adjacent end portions of two car bodies are supported by a single truck, the latter being known in the art as a pivot truck, and this invention contemplates certain improvements in the construction shown in patent to A. W. Clarke, Number 1,879,093, September 27, 1932.

One object of this invention is the provision of a connection for the adjacent end portions of adjacent bodies of an articulated car which will maintain the end portions in their proper relative positions and, at the same time, permit the bodies to turn or pivot relative to each other when rounding curves.

Another object of this invention is the provision of a truck for supporting the adjacent end portions of adjacent railway car bodies, said truck including a pair of truck bolsters each of which is adapted to support the end portion of one car body, the truck also including a transom arranged intermediate the bolsters and provided with a casting mounted thereon in such a manner as to be longitudinally movable with respect thereto upon relative movement of the adjacent end portions of adjacent car bodies, the latter being provided with adjacently arranged interconnected body connection castings which project into the truck centering casting.

A further object of this invention is the provision of new and improved side bearing means for supporting the adjacent end portions of adjacent car bodies against excessive rocking movement.

This invention also contemplates the provision of new and improved means for connecting the adjacent end portions of adjacent car bodies to a railway car truck.

Other objects and advantages of this invention will be apparent from the following description taken in conjunction with the accompanying drawings, in which

Figure 1 is a top plan view of the end portions of adjacent car bodies, certain parts being shown in section, other parts being broken away, and still other parts being omitted in order to more clearly show the invention;

Fig. 2 is a longitudinal sectional view through the articulated joint;

Fig. 3 is a sectional view taken on the line 3—3, Fig. 2.

Referring now more particularly to the drawings in which similar characters of reference designate similar parts in the several views, the adjacent end portions of two car bodies are

shown at A and B, the bodies having an under-frame which includes center sills 2 and an end sill of any preferred or desired construction.

The adjacent ends of the car bodies are provided with doorways framed by channels 4, one flange of each of the channels being extended beyond the car end to define an attaching means 6 for a flexible diaphragm 8, as shown clearly in Fig. 1, said diaphragm defining a closed passage-way between the adjacent bodies A and B.

The adjacent end portions of the car bodies A and B are supported by a common or pivot truck indicated generally at C which is provided with a pair of independent spaced lateral motion bolsters 10, one arranged under the end portion 15 of each car body as more clearly shown in Fig. 2. The bolsters extend between the side frames 12 of the truck and are supported by springs 14 positioned in spring seats 15 carried by a spring plank 16. The spring seats 15 are supported through the medium of swing links 18 pivotally mounted on a pin 20 supported in brackets 22 secured as by rivets 24 to the upper surfaces of outside transoms 26; the brackets 22 constituting parts of attaching castings 30 which are secured as by rivets 32 to the upper portions of the side frames 12 of the truck as clearly shown in Figs. 1 and 3. The beforementioned outer transoms 26, as shown more clearly in Fig. 2, are pressings of substantially channel shape as shown clearly in Fig. 2, and they are arranged respectively adjacent the outer side walls of the bolsters 10. Between the bolsters 10 is a center transom 34 of substantially I-beam shape secured to the side frames 12 by attaching castings 36 (see Figs. 1 and 3); said attaching castings 36 being provided with bearings 38 through which or between which the beforementioned pins 20 extend as shown also in said Figs. 1 and 3.

From the description above it can be seen that the construction of the present invention includes a side frame having a pair of independent spaced lateral motion bolsters 10 and between said bolsters a transom is arranged and adjacent the opposite side walls of the bolsters are transoms termed outer transoms. The pin 20 is supported by the several transoms 26 and 34 and, at the center transom 34 the pin supports swing links indicated at 40, see Figs. 1 and 2, the links 18 and 40 supporting the stirrups 41 by which spring planks 16 and seats 15 are carried.

Secured to the upper flange 42 by means of fasteners 44 is a wear plate 46 the side edge portions of which extend beyond the upper flange 42 and said wear plate is adapted to slidably sup-

port a truck center casting 48, the latter comprising a socketed body portion 50 having oppositely arranged flanges 52 depending therefrom with the lower portions thereof inturned to constitute flanges 54 underlying the side edge portions of the wear plate 46. From this description it will be apparent that the truck center casting is mounted for sliding movement on transom 34.

10 Each bolster 10 is provided with a bearing 56 secured to its upper surface, said bearings each being generally arcuate in form as shown more clearly in Fig. 1 and being adapted to receive segmental body bearings 58 depending from the 15 end portions of the respective car bodies. In the instance shown the body bearings are formed integral with the bottom walls 59 of body connection castings indicated generally at D and which are secured to and form parts of the body underframes. These connection castings D are generally of the form shown in the aforementioned 20 patent to Clarke 1,879,093 but differ from the construction shown in the Clarke patent in providing wear plates 60 at their forward end portions. 25 The castings D at their front end portions are provided with depending arcuate projections 62 which extend into the beforementioned truck center casting 50 and, as shown clearly in Fig. 2, the projections are interconnected through a 30 tongue and groove arrangement illustrated at 64 and 66 respectively; this in accordance with the disclosure in the beforementioned Clarke patent and resulting in a construction in which the car bodies are restrained against relative vertical shifting though permitting required relative 35 rotative movement.

Secured to the car bodies and depending therefrom as shown clearly in Fig. 3 are body side 40 bearings 68 having wear plates 70 secured to the lower surfaces thereof adapted to cooperate with wear plates 72 forming parts of truck side bearings illustrated generally at 74 and constituting integral upstanding parts formed at the end portions of the truck bolsters 10. The body side 45 bearings 68 are hollow as shown at 76 and constitute reservoirs holding a suitable lubricant which is adapted to lubricate the cooperating surfaces of wear plates 70 and 72, the lubricant being adapted to pass to these cooperating surfaces through openings 78 formed in the body side 50 bearings. To introduce lubricant into the side bearings 68 feed openings 73 are provided which are normally closed by plugs 75.

The bolsters 10, as more clearly shown in side 55 elevation in Fig. 3, are provided with a raised portion 80 intermediate the ends thereof on which the bearings 56 are mounted and said bolsters slope sharply downwardly from the raised portion 80 as shown at 82 and then upwardly to 60 form the truck side bearings 74; this downwardly inclined portion providing a space for receiving the pins 20 supporting the swing links 18 and 40.

Extending between adjacent car bodies is a foot 65 plate 84 supported by brackets 86, Z-shaped in cross section and resting upon end top cover plates 88 secured to the castings D. Clips 90 are secured to the cover plates 88 and overlap the lower flange of the Z-shaped bracket 86 to retain 70 the bracket and foot plate 84 against displacement. Secured to the adjacent end portions of the car bodies, as clearly shown in Figs. 1 and 2, are tread castings 89, substantially Z-shaped in cross section, the upper flanges 91 of which overlap 75 the marginal edge portion of the foot plate 84.

In service, with the parts arranged as shown in Fig. 2, the body A is permitted to swivel relative to body B due to the engagement of the body connection casting with the bearing 56 on bolster 10. Should track curvature be such as to necessitate a horizontal shifting movement of the interengaged body connection castings relative to the truck it will be obvious that this is permitted due to the sliding connection of the center casting 48 with the transom 34 on which 10 said casting is mounted. Sidewise tilting of the car bodies relative to the truck is limited by the new and improved design of side bearing arrangement as shown in Fig. 3.

The drawings show certain embodiments of 15 this invention but it is to be understood they are for illustrative purposes only and various changes in the form and proportions of the construction may be made within the scope of the appended claims without departing from the spirit of the 20 invention.

What is claimed is:

1. In an articulated car, a pair of car bodies arranged end to end, a truck for supporting the adjacent end portions of said bodies, and means 25 for connecting said bodies and truck comprising a laterally shiftable pivot between said end portions, a pair of lateral motion bolsters each arranged beneath one end portion of one of said bodies, an interengaged body and truck bearing 30 between said end portions and bolsters adapted to permit horizontal swiveling movement of the bodies in a confined path, said pivot being the center of swiveling movement.

2. In an articulated car, a pair of car bodies 35 arranged substantially end to end, a truck for supporting the adjacent end portions of said bodies, and means for connecting said bodies and truck comprising a pivot between said end portions, means on which said pivot is mounted 40 for shifting movement transversely of the truck, a pair of lateral motion bolsters each arranged beneath one end portion of one of said bodies, bearings between said end portions and bolsters adapted to permit horizontal shifting movement 45 of the car ends, said pivot being the center of rotation regardless of its position, and inter-engaged projections on the car end portions for preventing excessive relative vertical shifting of said end portions.

3. In an articulated car, a pair of car bodies arranged end to end, a truck for supporting the adjacent end portions of said bodies, a pair of spaced lateral motion truck bolsters, a transom 55 rigidly secured to the truck and arranged between said bolsters, a socketed truck center casting slidably mounted on said transom, means restraining said center casting against vertical movement relative to the transom, bearings between the end portions and bolsters so formed as 60 to permit horizontal rotation of the car end portions, said truck center casting constituting the center of rotation, and inter-engaging projections on the car end portions extended into the truck center casting and adapted to prevent excessive relative vertical shifting of the car bodies.

4. In an articulated car, a pair of car bodies arranged end to end and provided with contiguously arranged buffering surfaces, the adjacent end portions of said bodies having vertically depending pivot elements arranged in inter-engaged relation, and a truck center casting supported for independent transverse movement relative to the truck into which said pivot elements extend.

5. In an articulated car, a pair of car bodies arranged end to end, a truck for supporting said car bodies and provided with a pair of spaced lateral motion bolsters, body connection castings 5 for said car bodies, bearings between said connection castings and bolsters adapted to permit horizontal rotation of the car end portions, a truck center casting slidably mounted between the bolsters, and inter-engaged projections 10 pending from the body connection castings and arranged in the truck center castings.
6. In an articulated car, a pair of car bodies arranged end to end, a truck for supporting the adjacent end portions of said car bodies and provided with a pair of spaced lateral motion bolsters, body connection castings secured to the adjacent end portions of said bodies, interengaged 15 body and truck bearings between said end portions and bolsters adapted to permit horizontal 20 swiveling movement of the bodies in a confined path, a truck transom intermediate the bolsters, a truck center casting slidably supported on said transom, projections depending from the body connection castings and extended into the truck 25 center casting, said projections being relatively so formed as to prevent excessive relative vertical movement of the car bodies, truck side bearing elements formed integral with the bolsters at opposite end portions thereof, and lubricant holding 30 body side bearings secured to the car bodies and adapted to cooperate with the truck side bearings to prevent excessive rocking movement of the bodies relative to the truck, said body side bear-

ings being provided with means permitting passage of lubricant from the body side bearings to the contacting surfaces of the body and truck side bearings.

7. In an articulated car, a plurality of car bodies, a truck for supporting the adjacent end portions of said bodies, said truck being provided with a pair of independent lateral motion bolsters by which the car bodies are respectively supported, body connection castings secured to the adjacent end portions of said bodies, projections 5 depending from said castings, and a truck center casting arranged intermediate the bolsters and with which the depending projections cooperate, said truck center casting being slidably 10 supported whereby to be capable of shifting movement upon variation in the positions of the bolsters.

8. In an articulated car, a plurality of car bodies, a truck for supporting the adjacent end portions of said bodies, said truck being provided with a pair of independent lateral motion bolsters by which the car bodies are respectively supported, body connection castings secured to the adjacent end portions of said bodies, projections 20 depending from said castings, a truck transom arranged intermediate the bolsters, and a truck center casting with which the depending portions 25 cooperate slidably mounted on said transom whereby to be capable of lateral shifting movement upon variation in the positions of the 30 bolsters.

JOHN CHRISTIANSEN.
